US0D1059064S

(12) **United States Design Patent** (10) **Patent No.:** **US D1,059,064 S**
(45) **Date of Patent:** **** Jan. 28, 2025**

(54) **CHAIR**

(71) Applicant: **& Tradition A/S**, Copenhagen (DK)

(72) Inventor: **Jørgen Hee Welling**, Copenhagen (DK)

(73) Assignee: **& Tradition A/S**, Copenhagen K (DK)

(**) Term: **15 Years**

(21) Appl. No.: **29/815,139**

(22) Filed: **Nov. 11, 2021**

(30) **Foreign Application Priority Data**

May 12, 2021 (EM) 008538409-0008

(51) **LOC (15) Cl.** **06-01**

(52) **U.S. Cl.**

USPC **D6/375**
